US00D797763S

(12) **United States Design Patent** (10) **Patent No.:** **US D797,763 S**
Kim et al. (45) **Date of Patent:** **** Sep. 19, 2017**

(54) **DISPLAY SCREEN OR PORTION THEREOF
WITH GRAPHICAL USER INTERFACE**

(71) Applicant: **Samsung Electronics Co., Ltd.**, Suwon-si (KR)

(72) Inventors: **Yunkyoung Kim**, Suwon-si (KR); **Jinah Kong**, Daegu (KR); **Yerin Park**, Seoul (KR); **Donggoo Kang**, Seoul (KR); **Yongyeon Lee**, Suwon-si (KR)

(73) Assignee: **SAMSUNG ELECTRONICS CO., LTD.**, Suwon-si (KR)

(**) Term: **15 Years**

(21) Appl. No.: **29/562,130**

(22) Filed: **Apr. 22, 2016**

(30) **Foreign Application Priority Data**

Nov. 6, 2015 (KR) 30-2015-0056185

(51) LOC (10) Cl. **14-04**

(52) U.S. Cl.

USPC **D14/485**

(57) **CLAIM**

The ornamental design for a display screen or portion thereof with graphical user interface, as shown and described.

DESCRIPTION

The sole FIGURE is a front view of a display screen or portion thereof with graphical user interface showing our new design.

The broken lines in the drawings show a display screen or portion thereof and portions of the graphical user interface that form no part of the claimed design.

1 Claim, 1 Drawing Sheet
